UNITED STATES PATENT OFFICE.

CARL R. CROSSEN, OF BELL, CALIFORNIA.

APPARATUS FOR HANDLING WELL CASINGS.

Application filed January 26, 1927. Serial No. 163,770.

My invention relates to apparatus for handling well casings of the character embodied in my copending application Serial No. 163,769, filed Jan. 26, 1927.

It is a purpose of my present invention to provide an apparatus for handling well casing and similar forms of well tubing while in a well and through the medium of the conventional rotary drill pipe, my invention being characterized from that embodied in my copending application by the substitution for the hydraulic means of a mechanical means for actuating the instrument to engage or disengage the well casing.

I will describe only one form of apparatus for handling well casing embodying my invention and will then point out the novel features thereof in claims.

In the accompanying drawings,

Figures 1, 2 and 3 are fragmentary vertical sectional views and continuations of each other showing one form of apparatus for handling well casing embodying my invention in applied position to a drill pipe and well casing;

Figures 4, 5 and 6 are transverse sectional views taken on the lines 4—4, 5—5, and 6—6 of Figures 2 and 3;

Figure 7 is a view similar to Figure 2, showing a different position of the apparatus from that shown in Figure 2;

Figure 8 is a continuation of Figure 7 and a view similar to Figure 3, but showing the instrument of the apparatus in contracted position.

Similar reference characters refer to similar parts in each of the several views.

Referring specifically to the drawings, and particularly to Figures 3 and 8, my invention, in its present embodiment, is shown as comprising an instrument for handling well casing similar in principle of operation to the instrument embodied in my copending application hereinbefore referred to in that it is capable of occupying a contracted position, as shown in Figure 8, in which it is freely insertible into a well casing W and in an expanded position, as shown in Figure 3, in which it engages the well casing for handling of the latter. This instrument, in the present instance, is a fishing tool, but it is to be understood that it may be a perforating tool or any other form of tool capable of handling well casing. The instrument comprises four slips 15 having inclined inner surfaces 16 provided with grooves 17 in which work tongues 18

formed on an expander element 19, the latter being square in cross section, as shown in Figure 6, and provided with a conical lower end, as shown in Figure 3. The grooves 60 17 and the tongues 18 are dove-tailed in form, as shown in Figure 6, in order to provide an operative connection between the expander element and the slips, so that as the former is moved upwardly from the position shown in Figure 8 to that shown in Figure 3, the slips will be moved to expanded position to engage and securely grip the inner wall of the well casing W. The expander element 19 is provided 70 with an upwardly extending stem 20 which is squared in cross section, as shown in Figure 5, and which is provided with a collar 21 movable in grooves 22 of the slips 15 to abut a shoulder 23 at the lower ends of the grooves 75 and to thereby limit the downward movement of the expander element to the position shown in Figure 8. The upper ends of the slips are provided with heads 24 movably supported in a collar 25 threaded on the lower end of a tubular body 26 provided with pockets 27 receiving springs 28 which engage the heads 24 to yieldably urge the slips to expanded position. A centering bell 29 is threaded on the 80 collar 25, and this bell is designed for the 85 purpose of centering the instrument in its downward movement with respect to the well casing W so that it can be readily inserted into the upper end of the latter.

The lower end of the body 26 is provided 90 centrally with a squared opening 30 which slidably receives the stem 20. The stem is extended upwardly beyond the opening 30, where it is screw-threaded, as indicated at 31, for engagement by a tubular shaft 32 formed 95 of sections to facilitate assembling and interiorly screw-threaded, as indicated at 33, so that when rotated the stem can be moved upwardly or downwardly, depending upon the direction of rotation of such shaft. This 100 shaft 32 is supported in ball bearings 34, and its upper end is provided with a collar 35 to receive and have splined connection with the lower end of a driven shaft 36, in order that rotation of the latter will effect rotation of the tubular shaft 32, yet permitting longitudinal 105 adjustment of the driven shaft.

As shown in Figure 2, the upper end of the body 26 is threaded associated with a connecting member 37 constructed to rotatably 110 receive the driven shaft 36 and provided with a chamber 38 containing a centering and spac-

ing sleeve 39 for an expansible spring 40, the upper end of which latter bears against a ball bearing 41 associated with the flange of a cap 42 rotatably embracing a collar 43 of the shaft 36, and thereby causing the spring 40 to function in yieldably urging the shaft upwardly to the position shown in Figure 7.

A barrel 44 is threadedly connected at its lower end to the connecting member 37, and in this barrel is contained a reversing gear connection, including a tubular casing 45 constructed to accommodate a frame 46 having a collar 47 threadedly connected to the cap 42. This frame 46 is constructed to provide mountings for stub shafts 48 carrying planetary pinions 49 which constantly mesh with bevel gears 50 and 51. As clearly shown in Figure 2, the upper end of the driven shaft 36 extends into the frame and is squared to receive the gear 50. The gear 51 is mounted on the lower and squared end of a driving shaft 52, which likewise extends into the frame, so that the adjacent ends of the two shafts are in confronting relation to each other. The driving shaft is provided with a collar 53 rotatable in a cap 54 provided on the frame 46.

The upper end of the casing 45 is provided with teeth 55 which are adapted to mesh with teeth 56 on a collar 57 formed at the lower end of a tubular driving connector 58. The driving shaft 52 extends into the driving connector 58 and is adapted for operative connection therewith by two keys 59 and 60, either of which is adapted to engage within any one of a plurality of grooves 61. The construction and arrangement of the grooves is clearly shown in Figure 4. The keys 59 and 60 are disposed in pockets 62 formed in the shaft 52 but are normally urged to projected positions by a spring 63. The keys are mounted on resilient arms 64 secured to the shaft 52, and the opposite ends of the keys are beveled as indicated at 65 in order to permit unrestricted longitudinal movement of the driving connector 58 to engage or disengage either of the keys. The teeth 55 of the casing 45 are also adapted to engage teeth 66 on a stationary sleeve 67 secured within the barrel 44 for a purpose to be described hereinafter.

As shown in Figure 2, the upper end of the barrel 44 is threadedly connected to a collar 68 through which the driving connector 58 extends. As shown in Figure 1, the upper end of the driving connector is threadedly connected to a collar 69, the latter in turn being threadedly connected to a rotary drill pipe 70. A partition 71 is formed in the collar 69 and provided with an opening normally closed by a plug 72, the opening providing means through which lubricant can be supplied interiorly of the driving connector 58 and, hence, to the movable parts of the apparatus.

The operation of the apparatus is as follows: As will be gained from the preceding description, the driving connector 58 through the medium of the collar 69 is adapted for connection to the lower end of a rotary drill pipe, the pipe being utilized to lower the apparatus into the well in order that the instrument carried thereby may be inserted to have handling engagement therewith. As the apparatus is lowered into a well the driving connector 58 or rather the collar 57 occupies the elevated position shown in dot-and-dash lines in Figure 2, in which it engages the collar 68 so that the entire apparatus is suspended from the collar. In this position of the driving connector, it is out of operative connection with the driving shaft 52, so that should the drill pipe be rotated its motion will not be imparted to the shaft 52. As the apparatus is lowered, the centering bell 29 finally engages and passes over the upper end of the well casing, thereby centering the lower end of the instrument with respect to the upper end of the well casing. Continued lowering with the instrument in the contracted position shown in Figure 8 permits the insertion of such instrument into the well casing, it being understood that the parts of the apparatus for actuating the instrument are in the positions shown in Figures 7 and 8.

To effect expansion of the instrument to cause the slips 15 to securely grip the casing or any section thereof, it is necessary to elevate the expander 19 from the position shown in Figure 8 to that shown in Figure 3, and this is accomplished in the following manner: By further lowering the drill pipe the driving connector 58 is lowered to the position shown in Figure 2 to cause the teeth 56 of the collar 57 to engage the teeth 55 of the casing 45, and to cause the key 60 to engage within one of the grooves 61 of the collar. It will be noted that in this position of the driving connector the weight of the entire drill pipe is imposed on the casing 45 to force the latter downwardly from the position shown in Figure 7 to that shown in Figure 3, in which the teeth 55 are moved out of engagement with the teeth 66, and the casing now reposes on the connecting member 37. By now rotating the drill pipe, the member 58, as well as the driving shaft 52, will be rotated in the same direction, thereby causing rotation of the reversing gear connection as a unit, which, as a consequence, causes rotation of the driven shaft 36 in the same direction as that of the driving shaft 52. With the driven shaft 36 rotating, it will be clear that the tubular shaft now functions through its threaded connection with the stem 20 to elevate the expander element 19 to the elevated position shown in Figure 3, whereby through the medium of 130

the tongue-and-groove connections with the slips the latter are moved to expanded position. With the instrument in this expanded position, it will be clear that by elevating the entire apparatus through the medium of the drill pipe the well casing can be withdrawn from the well.

To release the well casing while the latter is within the well or after it has been withdrawn therefrom, the instrument can be moved to the contracted position shown in Figure 8 by elevating the collar 57 through elevation of the drill pipe to the position shown in Figure 7, in which the key 59 engages within one of the grooves 61 to provide an operative connection between the driving connector 58 and the driving shaft 52. As the driving connector is elevated to this position, the weight of the drill pipe is removed from the casing 45, so that the spring 40 can now function to elevate the casing and the entire reversing gear connection to the position shown in Figure 7, in which the teeth 55 are moved into meshing relation to the teeth 66 of the sleeve 67, thus effecting locking of the casing against rotation within the barrel. Upon rotation of the drill pipe, the driving shaft 52 will be driven as before, but as the casing 45 is now locked against rotation the shaft 52 will be free to drive its gear 51, thereby driving the pinions 49 about their own axes and thus causing reverse rotation of the gear 50. In this manner, the driven shaft 36 is rotated in the reverse direction from that of the shaft 52, thereby causing the tubular shaft 32 to feed the stem downwardly to move the expander element to contracted position, and thereby permitting the withdrawal of the instrument from the well casing.

Although I have herein shown and described only one form of apparatus for handling well casings embodying my invention, it is to be understood that various changes and modifications may be made therein without departing from the spirit of the invention and the spirit and scope of the appended claims.

I claim as my invention:

1. An apparatus of the character described comprising an instrument capable of occupying either of two extreme positions, means for actuating the instrument, rotary means for operating the means in one direction or the other to move the instrument to one extreme position or the other, and means by which the rotary means is adapted for operative connection to a rotary drill pipe in a manner to be driven thereby in one direction or the other in response to unidirectional rotation of the drill pipe.

2. An apparatus of the character described comprising an instrument capable of occupying either of two extreme positions, screw means for actuating the instrument, a

two part shaft having a part connected to the screw means, a reversing gear connection between the shaft parts, and means by which the other part of the shaft is adapted for operative connection to a rotary drill pipe so as to utilize the unidirectional rotation of the drill pipe to drive the shaft part or the reversing gear connection as a whole whereby the screw means can be actuated to move the instrument to either of its extreme positions.

3. An apparatus of the character described comprising an instrument capable of occupying either of two extreme positions, screw means for actuating the instrument, a two part shaft, one part having a splined connection with the screw means to permit said part to occupy either of two extreme positions yet maintaining a driving connection therewith, a reversing gear connection between the shaft parts, a toothed casing for the reversing gear connection, a fixed toothed element, means for yieldably urging the casing to a position in which it has toothed engagement with the fixed element to cause the reversing gear connection to drive the splined shaft part in the same direction as the other shaft part, a driving member having a toothed head, and means to effect and maintain a driving connection between the other shaft part and the driving member in either of two positions of the latter, the driving member adapted for operative connection to a rotary drill pipe to be rotated thereby and movable by the drill pipe to one of its positions in which its head engages the casing and moves the latter out of engagement with the fixed element, or to the other position in which its head is out of engagement with the casing to allow the latter to engage the fixed element whereby the splined shaft part can be driven in one direction or the other and the screw means actuated accordingly to move the instrument to one extreme position or the other.

4. In an apparatus of the character described, an instrument capable of being inserted into a well casing and movable to occupy one position in which it grips the casing and another position in which it disengages the casing to permit the withdrawal thereof, screw means for actuating the instrument, a driven shaft for actuating the screw means, a driving shaft rotatable in one direction and adapted to actuate the driven shaft, a reversing gear connection between the shafts including a toothed casing, a stationary toothed member, a driving connector telescopically associated with the driving shaft to occupy two positions, means providing an operative connection between the driving connector and the driving shaft when the former is in either of its two positions, yieldable means for urging the reversing gear connection upwardly to cause the toothed casing

- to engage the toothed member for locking the casing against rotation, and a toothed element on the driving connector adapted to engage the toothed casing and to move the latter out of engagement with the toothed element when in one position of the driving connector whereby both the casing and gearing of the reversing gear connection are driven as a unit.
5. In an apparatus of the character described, an instrument capable of being inserted into a well casing and movable to occupy one position in which it grips the casing and another position in which it disengages the casing to permit the withdrawal thereof, means for actuating the instrument, a driven shaft for actuating said means, a driving shaft adapted to actuate the driven shaft, a reversing gear connection between the shafts including a casing, a stationary member, means on the casing and member for providing an operative connection between the two, a driving connector movable to occupy two positions, means providing an operative connection between the driving connector and driving shaft when the former is in either of its two positions, said reversing connection normally occupying one position in which said co-acting means operatively connects said casing and stationary member to lock the casing against rotation, and means on the driving connector adapted for operative connection with said co-acting means on the casing for providing an operative connection between the two and adapted to engage and move the casing to disrupt its operative connection with said stationary member when the driving connector is in one of its positions, whereby both the casing and gearing of said reversing connection are driven as a unit.
6. In an apparatus of the character described, an instrument capable of being inserted into a well casing and movable to occupy one position in which it grips the casing and another position in which it disengages the casing to permit the withdrawal thereof, means for actuating the instrument, a two part shaft, one part of which is movable to either of two positions, means for providing an operative connection between the first means and said shaft part in either of the latter's two positions, a reversing gear connection between the shaft parts and including a casing, a fixed element, means on the casing and element co-acting to provide an operative connection between the two, means for urging the casing to a position in which it has operative connection with said fixed element to cause said reversing gear connection to drive said shaft part in the same direction as the other shaft part, a driving member, means to effect and maintain a driving connection between the other shaft part and the driving member in either of two positions of the latter, the driving member adapted for operative connection to a rotary drill pipe to be rotated thereby and movable by the drill pipe to one of its positions in which it has operative engagement with co-acting means on the casing and moves the latter out of engagement with said fixed element, or to the other position in which the driving member is out of engagement with the casing to allow the latter to engage the fixed element whereby said first shaft part can be driven in one direction or the other and said first means actuated accordingly to move the instrument to one or the other of its positions.
7. An apparatus of the character described comprising an instrument capable of occupying either of two extreme positions, mechanical means by which rotary motion of a drill pipe is adapted to be utilized to move the instrument to either of its two extreme positions, and means for controlling the first means adapted for connection to the drill pipe and responsive to longitudinal movement of the latter to cause the first means to move the instrument either to one or the other of its positions according as the drill pipe occupies one position or another.
8. An apparatus of the character described comprising an instrument capable of occupying either of two extreme positions, means for actuating the instrument, a two part shaft having a part connected to the first means, a reversing gear connection between the shaft parts, and means by which the other part of the shaft is adapted for operative connection to a rotary drill pipe so as to utilize the unidirectional rotation of the drill pipe to drive the shaft part or the reversing gear connection as a whole whereby the first means can be actuated to move the instrument to either of its extreme positions.

CARL R. CROSSEN.
